UNITED STATES PATENT OFFICE

ROBERT C. HOPKINS, OF ALLIANCE, OHIO

ROTARY CUTTING, MIXING AND ATTRITION MILL

Application filed September 21, 1929. Serial No. 394,351.

The invention relates to mills for pulverizing, breaking up, mixing and screening the heavy particles of mineral, vegetable and animal matter in fluid or semi-fluid state and 5 more particularly to a mill especially adapted to be placed in an oil line to an oil burner or the like for continuously grinding and feeding oil from a source of supply to the burner.

10 The present improvement contemplates the upon the mill disclosed in my prior application, Serial No. 260,863, filed March 12, 1928, now Patent No. 1,764,020. In my former application the oil was admitted at right 15 angles to a shaft carrying a gang of circular saws and was fed to the saws in somewhat the same manner as a board would be brought into contact with a saw for ripping.

10 The present improvement contemplates the admission of the oil at one side and one end of the mill, the housing of which is divided into multiple chambers through which the oil is successively passed, a shaft extending longitudinally through the chambers, a series of 25 radial spikes being provided upon the shaft in the initial chamber and circular saws being fixed upon the shaft throughout the other chambers, the communicating ports between the chambers being alternately located 30 at diametrically opposite sides of the shaft.

The object of the improvement is to provide an apparatus which will cut, grind, shred and mix the heavy particles of the oil to such an extent that it is thoroughly mixed 35 of the same consistency and in condition to flow freely through the pipe lines, valves and other parts of the circulating system to an oil burner or the like.

An embodiment of the invention is illustrated in the accompanying drawing in which Figure 1 is a longitudinal sectional view through the improved mill;

Fig. 2, a transverse section taken on the line 2-2, Fig. 1; and

Fig. 3, a similar section taken on the line 3-3, Fig. 1.

Similar numerals refer to similar parts throughout the drawing.

50 The improved mill is provided with the housing, shown generally at 10, preferably

located in horizontal position and of greater height than its width, as best shown in Figs. 2 and 3. Bearings 11, which may be provided with suitable lubricating glands are attached to opposite ends of the housing 55 by screws or the like located through the flanges 12 of the bearings and into the end walls 13 of the housing.

The shaft 14 is located through the median line of the housing and journaled in the bearings 11, one end thereof protruding through the corresponding bearing whereby any suitable driving means may be operatively connected thereto for rotating the shaft in the direction of the arrows shown in Figs. 60 65 2 and 3.

The interior of the housing is divided into a plurality of chambers located in longitudinal succession throughout the length of the housing, as by the transverse partition walls 70 15 and 16 forming the initial chamber 17 and the secondary chambers 18 and 19.

The work of milling can be compounded, tripled, quadrupled or otherwise increased by the mere addition of secondary chambers, but for the purpose of illustration only two such chambers are shown. A hub 20 is fixed upon the shaft 14 within the initial chamber 17 and a plurality of radial spikes 21 are fixed in the peripheral portion of the hub. A plurality 75 of disk saws 22 are fixed upon the shaft extending through the chambers 18 and 19, these saws being preferably spaced as by the disks 23. The revolving cutter thus provided is axially disposed through all of the 80 85 chambers.

A collar 24 is fixed upon the shaft adjacent to one end of the housing and a similar collar 25 is fixed thereon separating the disk saws from the spiked hub 20, a clamping nut or the like 26 being located upon the shaft near the other end portion of the housing for clamping the hub and disks thereon.

The initial chamber 17 is provided with the inlet opening 27 which may be in the form of a threaded boss as shown in Fig. 3 for the connection of a pipe leading from a pump or other source of oil under pressure. A port 28 preferably located in the upper portion of the partition wall 15, forms a communication 90 95 100

between the chambers 17 and 18 while a similar port 29, located in the lower portion of the partition wall 16 forms a communication between the chambers 18 and 19. An outlet 5 30, being in the form of a threaded boss for the connection of a pipe leading to a burner or the like, provides for the discharge of the oil from the chamber 19.

In the operation of the mill the oil under 10 pressure is fed into the initial chamber 17, the spikes 21 giving the oil its first milling. The oil is then fed through the port 28 into the chamber 18 where it is again subjected to violent agitation, cutting and mixing by the 15 rotating disk saws.

After the oil has been subjected to this action it is discharged from the chamber 18 through the port 29, located at 180° from the port 28, passing into the chamber 19 where it 20 is again cut and milled by the action of the saw disks after which the ground and milled oil is discharged from the mill through the outlet 30.

It will be noted that the oil enters the mill 25 at one side and at one end of the mill and in the bottom portion of the initial chamber, passing to the chamber 18 from the top of the initial chamber and being discharged from the bottom of the chamber 18 into the chamber 19 passing from the mill at the other side and other end of the housing. The oil entering the one end of the housing and passing in 30 the tortuous path shown from one chamber to the next, being subjected to violent agitation, cutting and mixing by the successive action of the spikes and disk saws, and then 35 being discharged from the other end and other side of the housing, produces a uniformity of the mixture while at the same time permitting the oil to flow successively and continuously from one chamber to the next.

With this construction of mill it has been found that it is possible to obtain the most complete and efficient free flowing qualities 40 of the fluid mixture thus especially adapting the same to use in an oil line leading to a burner or the like where a continuous operation is necessary. The mill may be located either on the suction side or the pressure side of a 45 circulating pump and will actually aid the work of pumping by the cutting, grinding and milling effect, reducing the heavy particles of oil or the like to the consistency of free flowing liquid. Although a single port 50 is shown for providing communication between each of the chambers and the next adjacent chamber, it should be understood that a plurality of ports may be located through each partition wall if desired without detract- 55 ing from the effectiveness of the mill.

As best shown in Figs. 2 and 3 it will be seen that the saw disks 22, as well as the spikes 21, substantially contact with opposite sides of the housing, thus making it necessary for 60 the oil to pass between the disks or spikes and

the housing to pass from one chamber to the next, owing to the staggered relation of the ports in the chambers.

I claim:

1. A rotary mill including a housing divided into a plurality of communicating chambers, an oil inlet to one chamber, an oil outlet from another chamber, a plurality of revolving spikes in one chamber, and a plurality of revolving cutting disks in another chamber. 70

2. A rotary mill including a housing divided into a plurality of communicating chambers, an oil inlet to one chamber, an oil outlet from another chamber, a plurality of revolving spikes in one chamber, and a plurality of revolving saw disks in another chamber. 80

3. A rotary mill including a housing divided into a plurality of communicating chambers, an oil inlet to one chamber, an oil outlet from another chamber, a plurality of revolving spikes in the first chamber, and a plurality of revolving cutting disks in another chamber. 85

4. A rotary mill including a housing divided into a plurality of communicating chambers, an oil inlet to one chamber, an oil outlet from another chamber, a plurality of revolving spikes in the first chamber, and a plurality of revolving saw disks in another chamber. 90

5. A rotary mill including an elongated, substantially horizontal housing divided transversely into a plurality of chambers, an oil inlet at one end and one side of the housing into the first chamber, an oil outlet at the other end and other side of the housing from the last chamber, a communicating port from each chamber to the next chamber, and a revolving cutting member located through all of the chambers, the revolving cutting member being provided with spikes throughout a portion of its length. 100

6. A rotary mill including an elongated, substantially horizontal housing divided transversely into a plurality of chambers, an oil inlet at one end and one side of the housing into the first chamber, an oil outlet at the other end and other side of the housing from the last chamber, a communicating port from each chamber to the next chamber, and a revolving cutting member located through all of the chambers, the revolving cutting member being provided with spikes within the 110 first chamber. 115

7. A rotary mill including an elongated, substantially horizontal housing divided transversely into a plurality of chambers, an oil inlet at one end and one side of the housing into the first chamber, an oil outlet at the other end and other side of the housing from the last chamber, a communicating port from each chamber to the next chamber, and a revolving cutting member located 125 130

through all of the chambers, the revolving cutting member being provided with spikes within the first chamber and with saw disks within another chamber.

5. 8. A rotary mill including a housing divided transversely into a plurality of chambers, an oil inlet at one end portion of the housing into the first chamber, an oil outlet at the other end of the housing from the last chamber, a communicating port from each chamber to the next chamber and revolving cutting means located through all of the chambers whereby the oil is successively ground and mixed in each of the several 10 chambers, said ports being alternately located above and below the revolving cutting means.

9. A rotary mill including an elongated, substantially horizontal housing divided by 20 transverse partitions into a plurality of chambers located in longitudinal succession throughout the length of the housing, an oil inlet at one end of the housing into the first chamber, an oil outlet at the other end of the 25 housing from the last chamber, a communicating port from each chamber to the next chamber, and a revolving cutter member axially disposed through all of the chambers.

In testimony that I claim the above, I 30 have hereunto subscribed my name.

ROBERT C. HOPKINS.
